CLAIM

The ornamental design for a flow rate regulator unit, as shown and described.

DESCRIPTION

FIG. 1 is a bottom plan view of a flow rate regulator unit showing my new design;

FIG. 2 is a bottom, front perspective view thereof;

FIG. 3 is a top plan view thereof;

FIG. 4 is a top, front perspective view thereof;

FIG. 5 is front elevational view thereof;

FIG. 6 is a rear elevational view thereof;

FIG. 7 is a left side elevational view thereof; and,

FIG. 8 is a right side elevational view thereof.

The broken lines represent unclaimed portions of the flow rate regulator unit and do not form part of the claimed design.
